UNITED STATES PATENT OFFICE.

JAMES BARELS, OF DES MOINES, IOWA.

VAPORIZER.

1,110,866.

Specification of Letters Patent. Patented Sept. 15, 1914.

Application filed August 28, 1911. Serial No. 646,439.

To all whom it may concern:

Be it known that I, JAMES BARELS, a citizen of the United States, residing at Des Moines, in the county of Polk and State of Iowa, have invented a certain new and useful Vaporizer, of which the following is a specification.

The object of my invention is to provide a vaporizer especially designed for use in connection with automobiles.

More specifically it is my object to provide a vaporizer in which the heat from the engine exhaust pipe is employed for raising the temperature of a chamber to which gasoline is automatically fed in suitable quantities so that the gasoline may be vaporized by the heat and retained within the chamber at a pressure slightly in excess of atmospheric pressure so that the vapor thus generated may be retained under pressure to be delivered to the engine in such a manner that the supply of vapor is readily available at all times, even after the engine has remained stationary for a considerable period of time so that the engine may be started immediately without waiting for the vapor to be drawn into it through a vaporizer by suction in the ordinary manner.

A further object is to provide means for automatically maintaining the vapor within the chamber at a certain predetermined degree of pressure and to automatically control the flow of gasoline into the chamber by said pressure regulating means.

Another object is to provide means for automatically stopping the flow of gasoline into the chamber when the chamber is being held for a considerable period of time in an inclined position as, for instance, when the automobile is standing still on an inclined surface.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows a top or plan view of a vaporizer embodying my invention with the cover of the chamber removed. Fig. 2 shows a sectional view on the line 2-2 of Fig. 1. Fig. 3 shows an enlarged, detail, sectional view illustrating the float governor and the pressure regulator. Fig. 4 shows an en-

larged, detail, sectional view of the valve to be controlled by the pressure regulator. Fig. 5 shows an enlarged, detail, sectional view of the pressure regulator. Fig. 6 shows an enlarged, detail view of the butterfly valve for controlling the admission of heated vapors from the exhaust pipe into the heat pipes on the interior of the vaporizing chamber, and Fig. 7 shows an enlarged, detail, sectional view of the valve for controlling the supply of gasoline.

Referring to the accompanying drawings, I have used the reference numeral 10 to indicate a rectangular vaporizing chamber preferably made of sheet metal. Resting on top of same is a gasoline tank 11, the gasoline tank being connected with the vaporizing chamber by the gasoline supply pipe 12. The numeral 13 indicates an exhaust pipe from an internal combustion engine. Connected with the exhaust pipe is a pipe 14 for the hot vapors from the exhaust pipe, which pipe 14 is provided with a valve casing 15 containing a butterfly valve 16 controlled by a crank arm 17. The upper end of the pipe 14 communicates with a coupling 18 within the vaporizing chamber having four branches leading from it. Communicating with each of the four branches of the coupling 18 is a heat radiating device comprising a series of pipes 19 so arranged that hot vapors entering the coupling 18 may travel through in one of the pipes 19 exactly the same distance before reaching the discharge pipes 20 and 21. The preferred arrangement of these pipes is illustrated in Fig. 1 although various other constructions might be used, it being the purpose of this part of my device to provide for the exhaust vapors from the engine being divided and passing through each of the radiating pipes with approximately the same amount of hot vapors flowing through each pipe so that the entire radiating system is thus heated to the same degree.

All of the pipes comprising the radiating system are preferably covered with an absorbent material 22 such, for instance, as felt, as illustrated in Fig. 2. The felt covering for these pipes has been omitted from Fig. 1 so that the pipe may be clearly seen.

Arranged within the bottom of the vaporizing chamber is a series of layers of absorbent material 23 such as felt and they

are arranged in a plane below the radiating pipes 19, the absorbent material of the pipes being preferably placed in position in engagement with the layers of felt 23.

It is essential that the gasoline be maintained at approximately a certain predetermined level within the vaporizing chamber so that there is just sufficient gasoline to moisten the layers of felt 23 and the felt that surrounds the radiating pipes.

To provide for the regulation of the gasoline flow, I have arranged in the gasoline pipe 12 a valve 24 which, as illustrated in Fig. 7, is provided with a comparatively small valve opening 25 so arranged that a very slight turn of the valve stem 26 will be sufficient to either cut off the flow of gasoline or open the passageway through the valve. Connected with the valve stem 26 is an arm 27 to which is connected a float 28. Said parts are so arranged that when the float is elevated by an excessive quantity of liquid within the vaporizing chamber the valve will be closed and when lowered it will be opened.

I have also provided means for automatically closing the valve 24 when the vaporizing chamber is held stationary in a position out of a horizontal line such, for instance, as when the automobile in which the vaporizer is placed is standing on an inclined surface so that the vaporizer will not be flooded in the event that the vaporizing chamber is tilted in one direction. This device comprises a weighted bell crank lever 29 having a forked end 30 connected with the float. The said weighted bell crank lever is so arranged that if the vaporizing chamber is tilted in position with the right end, as shown in Fig. 3, elevated, the weighted lever will tend to close the valve and if the same end is lowered the weighted lever will coact with the float to open the valve. This weighted lever is counterbalanced with the float and hence it will only work to control the valve when the float is permitted to move downwardly on account of the absence of the supporting liquid in contact with it. Therefore the interior of the tank cannot be flooded when the gasoline is in engagement with the float but it is only when the tank is tilted in a direction for drawing the gasoline away from the float that the weight will operate to open the valve.

In order that the mixture of vapor and air that is supplied to the engine may be heated to the greatest extent possible so that it will be readily combustible within the engine cylinders, I have provided an air heating means comprising a jacket 30 surrounding a part of the engine exhaust pipe 13 and having one end open to admit air and the other end arranged in communication with a mixing valve 30^b which

is also connected to the vapor supply pipe 30^c which leads from the interior of the vaporizer tank and discharges into the mixing valve. The mixing valve of itself may be made of any ordinary construction. The advantage of having the mixing valve supplied with heated air to commingle with the heated vapor is that the combined product may be delivered to the engine cylinders in a heated condition so that it is more readily combustible than a cold mixture.

I have also provided means for maintaining the vapor within the vaporizing chamber, at a pressure slightly in excess of atmospheric pressure, and also in this connection I have provided means for forcing the gasoline into said vaporizing chamber against said pressure as follows: Connected with the gasoline supply pipe 12 is a valve casing 31. Within the valve casing 31 is a passageway 32 leading to a ball valve chamber 33 on which a ball valve 34 is placed to normally close the passageway by the weight of the ball. Leading from the ball valve chamber 33 is a passageway 35 leading to a chamber 36 in which is slidably mounted a piston 37. This piston is provided with a number of vertical passageways 38 in each of which is a ball valve 39 held upwardly against the valve seat by a spring 40. By this arrangement, it is obvious that when the piston 37 moves downwardly it will create enough suction within the chamber 36 and the passageway 35 to raise the ball valve 34 from its seat and to admit a quantity of gasoline into the chamber 36; then when the piston 37 is elevated the gasoline will force the ball valves 39 downwardly and thus permit the gasoline to flow downwardly through the valve into the vaporizing chamber.

Connected to the lower end of the piston 37 is a stem 41, which stem is extended through the regulator disk 42, in which disk is a spring 43 to hold the top of the disk 42 elevated. By this arrangement, it is obvious that when the vapor pressure within the vaporizing chamber increases to a certain point, the top of the disk 42 will be forced downwardly and the piston 37 will be moved downwardly and a fresh supply of gasoline will be introduced into the chamber 36; then when the pressure is reduced the spring 43 will elevate the upper portion of the disk 42 and the piston 37 will be forced upwardly, thus forcing a quantity of gasoline from the chamber 36 into the vaporizing chamber.

The amount of heat introduced into the vaporizing chamber controls the generation of vapor and in order to regulate the amount of heat thus admitted, I have provided on the stem 41 below the vaporizing chamber a bell crank lever 44 connected by a rod 45 with the crank 17 of the butterfly valve. By

this arrangement, when the pressure within the vaporizing chamber becomes too great, the butterfly valve is partly closed and the heated vapors are permitted to escape through the exhaust pipe.

It is to be understood that the vapor from the vaporizing chamber is to be mixed with air in proper proportions in any ordinary way before being admitted into the engine.

10 One of the advantages of my improvement is that there will always be a quantity of vapor under pressure contained within the vaporizing chamber so that when starting the engine vapor will be admitted into the 15 cylinders on the first piston stroke in proper condition to be ignited and exploded.

Another advantage is that by doing away with small needle valves and the like for controlling the supply of gasoline, I avoid 20 the danger of having the supply pipes clogged up on account of the presence of minute particles of foreign matter in the supply of gasoline.

Another advantage is that by the generation 25 of vapor in this manner, I am enabled to provide vapor in proper quantities for use in an engine whether the engine is used in extremely cold weather or in extremely warm weather as the outside has practically no effect upon the generation of vapor in my improved vaporizer.

I claim as my invention:

1. In a device of the class described, the combination of a receptacle, a radiator therein, means for supplying heat to the radiator, said radiator being spaced apart from the bottom of the receptacle, an absorbent cover for the radiator completely surrounding it, an absorbent material in contact with the 40 absorbent cover and filling the space between the absorbent cover and the bottom of the receptacle, means for supplying liquid fuel into the receptacle, and means for automatically limiting the height of the liquid 45 fuel so that it will not at any time completely cover the radiator, for the purposes stated.

2. In a device of the class described, the combination of a suitable receptacle, means 50 for introducing gasoline in limited quantities into it, a vapor outlet pipe, a radiator within the receptacle comprising a central coupling, an engine exhaust pipe communicating with the coupling, and a number of 55 radiator sections communicating with said central coupling and each provided with a number of pipes so arranged that the length of passageway from the coupling to the discharge end of each radiator section is exactly 60 the same, and discharge pipes communicating with the ends of said radiator sections.

3. In a device of the class described, the combination of a suitable receptacle, a radiator therein, means for conducting heated 65 vapors from an engine to said radiator, a

discharge pipe for the radiator, a gasoline inlet pipe for the receptacle, a valve on said gasoline inlet pipe, a float for operating said valve, a vapor discharge pipe for the receptacle, and a weighted lever arranged to co-operate with the float to close the valve in the gasoline supply pipe when the receptacle is tilted from a horizontal position. 70

4. In a device of the class described, the combination of a suitable receptacle, a radiator therein, means for conducting heated vapors from an engine to said radiator, a discharge pipe for the radiator, a gasoline inlet pipe for the receptacle, a valve on said gasoline inlet pipe, a float for operating said valve, a vapor discharge pipe for the receptacle, a weighted lever arranged to co-operate with the float to close the valve in the gasoline supply pipe when the receptacle is tilted from a horizontal position, and means 80 for automatically forcing gasoline in limited quantities into the interior of the receptacle against the pressure of the vapor therein. 85

5. In a device of the class described, the combination of a suitable receptacle, a radiator therein, means for conducting heated vapors from an engine to said radiator, a discharge pipe for the radiator, a gasoline inlet pipe for the receptacle, a valve on said gasoline inlet pipe, a float for operating said valve, a vapor discharge pipe for the receptacle, a weighted lever arranged to co-operate with the float to close the valve in the gasoline supply pipe when the receptacle is tilted from a horizontal position, and means 95 for automatically forcing gasoline in limited quantities into the interior of the receptacle against the pressure of the vapor therein, said means comprising a pressure regulator, a stem connected therewith and arranged to be reciprocated upon the fluctuation of the pressure regulator, and a pump device connected with said stem. 100

6. In a device of the class described, the combination of a suitable receptacle, a radiator therein, means for conducting heated vapors from an engine to said radiator, a discharge pipe for the radiator, a gasoline inlet pipe for the receptacle, a valve on said gasoline inlet pipe, a float for operating said valve, a vapor discharge pipe for the receptacle, a weighted lever arranged to co-operate with the float to close the valve in the gasoline supply pipe when the receptacle is tilted from a horizontal position, and means 115 for automatically forcing gasoline in limited quantities into the interior of the receptacle against the pressure of the vapor therein, said means comprising a pressure regulator, a stem connected therewith and arranged to be reciprocated upon the fluctuation of the pressure regulator, a pump device connected with said stem, said pump device 120 comprising a casing, a ball valve chamber, 125 and a pump device connected with said stem. 130

- ber at the top of the casing, a ball valve thereon, there being a chamber below the ball valve, and a passageway communicating between said chamber, a piston in the 5 lower chamber connected with said stem, said piston being provided with passageways throughout, and spring actuated valves in said passageway, substantially as and for the purposes stated.
- 10 7. In a device of the class described, the combination of a suitable receptacle, a radiator therein, an engine exhaust pipe communicating with the radiator, a butterfly valve in said pipe, a pressure regulator within the 15 receptacle, a gasolene supply pipe for the receptacle, means actuated by the pressure regulator for forcing gasolene into the receptacle when the pressure regulator is fluctuated, and means for controlling said butter-
- fly valve by the position of the pressure regulator, for the purposes stated. 20
8. In a device of the class described, the combination of a vaporizing chamber, an engine exhaust pipe to supply heat to the interior of the vaporizing chamber, a vapor 25 supply pipe leading from the vaporizing chamber, a mixing valve communicating with the vapor supply pipe, and a jacket surrounding the exhaust pipe and being open to admit air and having one end arranged to discharge into the mixing valve, 30 for the purposes stated.

Des Moines, Iowa, May 29, 1911.
